UNITED STATES PATENT OFFICE.

CHARLES W. EMERY, OF PHILADELPHIA, PENNSYLVANIA.

BLOWER.

1,364,360

Specification of Letters Patent. Patented Jan. 4, 1921.

Application filed April 6, 1920. Serial No. 371,588.

To all whom it may concern:

Be it known that I, CHARLES W. EMERY, a citizen of the United States, residing at Philadelphia, in the county of Philadelphia and State of Pennsylvania, have invented new and useful Improvements in Blowers, of which the following is a specification.

The invention relates to blowers and more particularly to fan blowers and has for an object to provide a blower for use in creating a blast of air, the blower being particularly adapted for blowing dust, dirt or other undesirable accumulations from machinery such as electric motors and the like.

15 To the desired end, use is made of a body provided with a chamber having means for creating the desired blast of air, together with a nozzle extended from the chamber to convey the air to the point of disposition or 20 exhaust, the body being provided with a handle so disposed that the entire device will be well balanced when grasped by the handle, thus greatly facilitating its manipulation.

25 In the further disclosure of the invention, reference is to be had to the accompanying drawings, constituting a part of this specification, in which similar characters of reference denote corresponding parts in all the 30 views, and in which,—

Figure 1— is an elevation of the device.

Fig. 2— is a plan view.

Fig. 3— is a fragmentary horizontal sectional view taken on the line 3—3 of Fig. 1.

35 Fig. 4— is a vertical transverse sectional view taken substantially on the line 4—4 in Fig. 1, and

Fig. 5— is a fragmentary elevation of a particular type of nozzle piece.

40 Referring more particularly to the views the blower in its entirety is indicated by the numeral 10 and comprises a body 11 of a somewhat circular configuration and having an off-set nozzle 12. The body 11 provides a chamber 13, one opening 14 thereto, being bordered by an upstanding circular flange 15 forming a seat for a motor 16 and the casing 17 thereof, the motor casing being suitably screwed or otherwise secured 45 to the body 11. The opposite face of the body has an opening 18 bordered by a circular flange 19, and over this opening is disposed a screen 20, secured in place by a ring 21, suitably screwed or otherwise secured to 50 the body so that the screen will be interposed between the flange 19 and the ring 55 21, suitably screwed or otherwise secured to the body so that the screen will be interposed between the flange 19 and the ring 21.

21 The motor may be of any suitable type and provides a fan 22 which when the motor is attached to the body, will extend into the chamber 13. The nozzle 12 where it is formed with the chamber, has a mouth 23 of considerable size, gradually tapering to a small outlet end 24 and at which point a nozzle piece 25 is attached. This nozzle piece may consist of a flexible hose 26 or 60 may be of a stiff material such as hardened rubber providing a nozzle piece 27 having an attaching end 28 for the nozzle 12 with the other end of the nozzle piece elongated as at 29.

The body 11 has a handle 30 which is preferably formed as an integral part of the body and this handle it will be seen by careful reference to the views, is off-set from the longitudinal plane of the body 11 by reason 75 of the off-setting portions 31, so that the handle proper 32 although extending parallel to the longitudinal plane of the body 11, projects rearwardly from the body as shown. This form of handle construction 80 is a particularly novel feature of my device, in that by off-setting the handle as shown, the weight of the motor will tend to be distributed so as to balance the entire structure 85 in the handling thereof, whereas if the handle extended merely rearward from the body, the excessive weight of the motor to one side of the handle and body would tend to tilt the entire device, preventing easy manipulation thereof.

It will of course be understood that when the motor is actuated the fan 22 will be subjected to a very rapid rotation, thus causing a suction of air through the opening 18 into the chamber 13 which air will be impelled by the rapidly rotating fan to be projected through the nozzle 12 and nozzle piece so that when the nozzle piece is brought into close contact with a dusty or dirty part of a piece of machinery the accumulations 190 will be rapidly removed from the machinery, as for instance in the case of a commutator on a motor, and in which instance the accumulation of dirt or dust ordinarily greatly impairs the operation of the motor. With 195 my device the blast of air will be sufficient to remove such accumulations and machinery of this character can be easily kept free from carbon or other dust.

It will be apparent that I prefer to use 200 any desired form of motor with my form of device and the particularly novel feature

is the construction and arrangement of parts forming the body 11, including the formation of chamber or nozzle and the disposition of the handle for the manipulation of 5 the article.

It will of course be understood that the motor 16 is operated by a suitable electric current which can be conveyed to the motor by the cable 16^a, having a plug 16^b for connection with those parts of the machinery of the motor which will insure rotation of the fan when the current is supplied to the motor.

Finally in order to aid a better suction of 15 the air through the opening 18, I preferably form thereabout an inwardly flared lip or flange 18^a which directs the air to the central part of the fan 22, the blades whereof are notched out at 22^a to accommodate 20 said lip or flange 18^a.

Having described my invention, I claim—

A blower comprising a round body portion having opposed openings and a nozzle leading from the body and terminating in a restricted outlet mouth, one of said openings having an inwardly flanged edge, a articulated plate covering this opening, means for removably securing the plate to the body, the opposite side of the body having a motor attached thereto, the shaft of which 25 entering the opening therein, blades on said shaft having their edges notched to receive therein the referred to inturned flange, and a bail-shaped handle extending outwardly from the body from the portion thereof to 30 which the motor is attached, and the inner arms of the said handle being disposed in contacting engagement with the motor.

In testimony whereof I affix my signature,
CHARLES W. EMERY.
